ROY D. MAILEY, OF EAST ORANGE, NEW JERSEY, ASSIGNOR TO COOPER HEWITT
ELECTRIC COMPANY, A CORPORATION OF NEW JERSEY.

TIME SWITCH.

Application filed October 30, 1923. Serial No. 671,637.

This invention relates to electric switches in which the circuit is completed through a conducting liquid and more particularly to that type in which a liquid flowing within 5 a switch for a definite period of time is used to predetermine by means of this definite period the time when the circuit is to be made or broken. It relates further to a device of this character through which the 10 liquid flows slowly in one direction but quickly in another, and one which can be quickly restored to its normal condition.

In my device the construction is similar to that of an hour glass except that there is 15 provided an additional passageway between the bulbs thereof. This additional passageway is not flow restricting as is the other but is of comparatively much larger cross section so as to provide a way for the rapid 20 passage of the material flowing from one bulb or reservoir to the other. The flowing material is preferably mercury but may be any suitable mobile material. And the switch is so constructed that when the liquid 25 has substantially reached an equilibrium after flowing through the smaller of the two passages that an electric circuit is closed.

As a means of securing a slow and predetermined period of flow in one direction 30 through my device, the construction thereof is not limited, however, to one having one passageway of small cross section. The same result may be attained by having a device with two reservoirs connected through two 35 passageways of comparable size but in one of which are inserted valves for controlling the time of flow of the liquid in one direction.

In the accompanying drawings Fig. 1 40 shows an embodiment of my invention in which are two reservoirs of substantially the same capacity which are connected by two tubes one of which is of very small cross section and the other of a comparatively 45 much larger cross section.

Fig. 2 shows another form of my invention in which the two connecting tubes are of about equal cross section but one of which is constricted to a much smaller cross section at one point or a certain distance of its length.

Referring to Fig. 1 part 1 is a reservoir 50 near whose lower and upper extremities are the terminals of two electric conductors 5 and 6 respectively. The top of 1 is con-

nected into a tube 3 which extends upwardly and is connected to the top of reservoir 2 through the side tube 8. The bottom of 2 is connected into the tube 11 which is of quite small cross section and which in some cases 60 is a capillary tube. This tube 11 extends downwardly and is connected into the bottom of 1 through side tube 12. There is sufficient mercury 13 in the device to be at a level above the lower end of wire 6 when 65 the device is substantially in the circuit closing position.

In Fig. 2 parts 4 and 7 connect the bottom of reservoir 2 to the bottom of reservoir 1. Tube 4 has a constriction 10, the opening 70 9 of which is of quite small cross section.

In the operation of my device for closing a circuit at a deferred time or after a predetermined period of time the switch is inverted from the position shown in Fig. 1. 75 In such position the mercury will have flowed to the other end of the device from which place when the switch is righted the mercury is returned through tube 11 to reservoir 1 for closing the switch within a definite interval after mercury flow commences. To insure that all the liquid passes into reservoir 2 the device should be returned to the original position by a clock wise motion in substantially the plane of tubes 3 and 11. 80 The mercury 13, or whatever material is used, now being in reservoir 2 and the device having been returned to the original position as shown in Fig. 1, the liquid flows downwardly through tube 11. But as the 85 bore of said tube 11 is of quite small cross section a predetermined appreciable time will elapse before there is sufficient liquid 90 in reservoir 1 to complete the circuit between conductors 5 and 6.

It may sometimes be desired to have the switch function in different periods of time. This may be done by setting the switch in the operating position at different angles varying from substantially the vertical to 100 approaching the horizontal position. The location of the terminals of conductors 5 and 6 and the quantity of liquid in the device of course if such as to insure the closing of the circuit at any of the positions desired. For 105 some purposes I vary the time flow through tube 11 by using tubes of various diameters or lengths.

Another way of varying the operating time of a given switch is to tip it not into the 110

inverted vertical position but to tip it at an angle between that and the normal vertical. Such a position might be substantially horizontal with the tube 11 below tube 3 in a vertical plane. As in this position a part of the liquid will flow into reservoir 2 through tube 3 and a part through tube 11 it will take a definite amount of time for the liquid to completely flow into reservoir 2 or to come to equilibrium. If the switch is returned to the operating position before this time has elapsed the deferred, or operating, time of the switch from the horizontal will be different varying according to the amount of liquid that got into the reservoir 2. However, since the liquid flows slowly through tube 11 as compared to tube 3 these variations may well be within limits suitable for most purposes.

20 I claim as my invention:

1. In an electric switch comprising a sealed glass envelope, in combination, two reservoirs one placed above and to one side of the other, a tube substantially L shaped connecting the top of one reservoir to the top of the other, another L shaped tube of

considerably smaller cross section connecting the bottoms of the two reservoirs, and a pair of electrical conductors sealed into said envelope and terminating within said lower reservoir, and a liquid conductor in sufficient quantity to make connection between the two said conductors.

2. In an electric switch comprising a sealed glass envelope, in combination, two reservoirs one placed above and to one side of the other, a tube substantially L shaped connecting the top of one reservoir to the top of the other, another L shaped tube of considerably smaller cross section connecting the bottoms of the two reservoirs, a pair of electrical conductors passing through the walls of the device whose terminals are located respectively near the top and near the bottom of the lower of the two reservoirs, and a liquid conductor in sufficient quantity to make connection between the two said conductors.

Signed at Hoboken, in the county of Hudson and State of New Jersey, this 29th day of October, A. D. 1923.

ROY D. MAILEY.
